FIG. 3 is a rear view of the design in FIG. 1;

FIG. 4 is a left side view of the design in FIG. 1;

FIG. 5 is a right side view of the design in FIG. 1;

FIG. 6 is a top view of the design in FIG. 1;

FIG. 7 is a bottom view of the design in FIG. 1;

FIG. 8 is a perspective view of the design in FIG. 1 when the edge protection material is coiled;

FIG. 9 is a front view of the design in FIG. 8;

FIG. 10 is a rear view of the design in FIG. 8;

FIG. 11 is a left side view of the design in FIG. 8;

FIG. 12 is a right side view of the design in FIG. 8;

FIG. 13 is a top view of the design in FIG. 8;

FIG. 14 is a bottom view of the design in FIG. 8;

FIG. 15 is a perspective view a second embodiment of the edge protection material for sheet coils;

FIG. 16 is a front view of the design in FIG. 15;

FIG. 17 is a rear view of the design in FIG. 15;

FIG. 18 is a left side view of the design in FIG. 15;

FIG. 19 is a right side view of the design in FIG. 15;

FIG. 20 is a top view of the design in FIG. 15;

FIG. 21 is a bottom view of the design in FIG. 16;

FIG. 22 is a perspective view of the design in FIG. 15 when the edge protection material is coiled;

FIG. 23 is a front view of the design in FIG. 22;

FIG. 24 is a rear view of the design in FIG. 22;

FIG. 25 is a left side view of the design in FIG. 22;

(Continued)

FIG. 26 is a right side view of the design in FIG. 22; FIG. 27 is a top view of the design in FIG. 22; and, FIG. 28 is a bottom view of the design in FIG. 22.
